(57) **CLAIM**

The ornamental design for a range hood, as shown and described.

DESCRIPTION

FIG. 1 is a top perspective view of one embodiment of a range hood.

FIG. 2 is a bottom perspective view of one embodiment of a range hood of FIG. 1.

FIG. 3 is a top view of one embodiment of a range hood of FIG. 1.

FIG. 4 is a front view of one embodiment of a range hood of FIG. 1.

FIG. 5 is side view of one embodiment of a range hood of FIG. 1.

FIG. 6 is a rear view of one embodiment of a range hood of FIG. 1.

FIG. 7 is a bottom view of one embodiment of a range hood of FIG. 1.

FIG. 8 is a top perspective view of a second embodiment of a range hood.

FIG. 9 is a bottom perspective view of a second embodiment of a range hood of FIG. 8.

FIG. 10 is a top view of a second embodiment of a range hood of FIG. 8.

FIG. 11 is a front view of a second embodiment of a range hood of FIG. 8.

FIG. 12 is a side view of a second embodiment of a range hood of FIG. 8.

FIG. 13 is a rear view of a second embodiment of a range hood of FIG. 8; and,

FIG. 14 is a bottom view of a second embodiment of a range hood of FIG. 8.

The features shown in broken lines depict environmental subject matter only and form no part of the claimed design.

1 Claim, 12 Drawing Sheets
